CURRENT COLLECTOR FOR TOY ELECTRIC
ROLLING STOCK

Richard G. Smith, Amsterdam, N. Y.

Original applications May 28, 1940, Serial No. 337,625, now Patent No. 2,373,148, dated April 10, 1945, and October 14, 1942, Serial No. 461,947. Divided and this application June 26, 1943, Serial No. 492,433

8 Claims. (Cl. 246—195)

This invention relates to wheeled toys or toy railway cars and to appurtenances associated with both the car and the track on which it runs for furnishing a toy electric train at selected or predetermined times with a special supply of electric current aside from that utilized for draft power, as for instance, to cause electrically powered actuation of some special apparatus carried by the car. The present application is divisional from my copending applications, Serial Nos. 337,625 and 461,947 filed May 28, 1940, and October 14, 1942, respectively, the former having eventuated in Patent No. 2,373,148 granted April 10, 1945.

One object of the invention is to equip a toy railway car with automatic actuating means electrically powered through track-side sources of current supply from which electrical energy may be picked up by the toy car as the latter passes predetermined points along the track. The invention aims for accomplishing this to provide current collecting toy parts of sufficiently simple construction and low cost to make possible a large quantity sale and production that will reduce consumer price. This is a prime requisite in toys.

A further object is to provide novel electric current transmitting means, including a simplified form of current collection shoe especially suited for toys, whereby mechanism for occasional use carried by the toy railway car may be caused to perform its special function at will and independently of the electric track circuit which supplies current for running the train, so that desired actuation of such mechanism can be caused to take place either while the car is running along its track or when the car stands stationary on the track.

My improved ways and means for attaining the foregoing and other objects will become clear from the examples thereof pointed out in the following description, in which description, reference is made to the accompanying drawings wherein all parts shown in section are assumed to be viewed in the direction indicated by arrows applied to the several section planes.

In the drawings:

Fig. 1 is a fragmentary plan view of a toy railway track with a portion of a toy freight car of the flat-car type riding thereon equipped with automatic unloading apparatus operable by a car-carried electromagnet.

Fig. 2 is a view taken in section on the plane 2—2 in Fig. 1.

Fig. 3 is a view taken in section on the planes 3—3 in Fig. 2.

Fig. 4 is an enlarged fragmentary inverted plan view taken partly in section on the plane 4—4 in Fig. 2.

Fig. 5 is an enlarged view of the fourth rail and associated track structure looking from the left at Fig. 3.

Fig. 6 is a view taken in section on the plane 6—6 in Fig. 5.

Fig. 7 is a diagram of electric circuits for supplying current to propel the train and independently to operate the car-carried unloading mechanism.

The toy railway car embodying the present improvements is indicated as a whole by 10 in Fig.

15 1. Whereas for simplicity its coupling parts or draft gear and the adjoining cars of its train are not shown, it will be understood that such may be of conventional form, the wheels of the cars and locomotive of the train riding on the two outside or traction rails 11 and 12 which are supported by, and may be in electrical contact with, the sleepers 13 as usual. The middle or "third" or power rail 14 supplies electric current to be picked up by the trolley or collector shoe of the toy locomotive and hence is insulated from the sleepers 13 and from traction rails 11 and 12 in any suitable manner as at 15.

Car 10 rolls on its usual form of toy traction wheels 16 whose axles support spaced trucks 17. The flat platform 19 of the car chassis rests pivotally on each of the trucks 17 in usual manner and as illustrated herein includes a top deck 20 which affords therebelow a shallow space 21 occupied by certain parts of the unloading mechanism.

The unloading mechanism consists mainly of three principal units including an elongated runway type of turn-tilt table 22 hinged on the fulcrum bracket 23 by means of the pivot pin 24. This fulcrum bracket rests on top of the deck 20 of platform 19 and swivels in relation thereto. The third main unit of the unloading mechanism comprises electromagnetic actuating means located under the car and designated as a whole by 27.

The U-shaped fulcrum bracket 23 consists of a bed wall 28 from either side of which upstands the spaced and tapering head walls 29 containing in their low ends holes for pivot pin 24 and in their high ends the detent notches 31 opening upward. A part of one head wall 29 is diverted horizontally to form a flat continuation of the bed wall 28 thereby affording a lug 35 containing a pivot hole offset considerably from the longitudinal center line of the bracket. Another part of

the head wall section of the bracket is turned downward instead of upward to form the tongue 37 by means of which the fulcrum bracket 23 is actuated.

As best shown in Figs. 1 and 2, the lug 35 of fulcrum bracket 23 is connected by a pivot stud 38 to the deck 20 of car platform 19 in a manner permitting the fulcrum bracket to swivel freely from its normal position shown by full lines in Figs. 1 and 2 to its unloading position crosswise of the car shown in Fig. 3 and by broken lines in Fig. 1. An aperture 34 in table 22 makes room for the head of pivot stud 38. This swiveling movement of the fulcrum bracket is limited to 90 degrees of swing by the engagement of the actuating tongue 37 of bracket 23 with opposite ends of an arcuate slot 39 in the deck 20 of the car platform, through which slot tongue 37 extends downward to be engaged by the actuating cam plate 43 within the shallow deck space 21. Cam plate 43 has a flange 42 fixed rigidly on and carried by the extreme end of a magnet plunger 44 which as best shown in Fig. 4 is slideable into and out of the magnet solenoid 45 of usual construction. This solenoid is rigidly mounted against the under surface of the platform deck 20 by means of one or more angle brackets 46 whose fastening rivets 47 are prevented from projecting above the top surface of deck 20 because occupying a slightly sunken or depressed panel space 48. A coiled spring 29 loosely surrounds plunger 44 and constantly exerts a thrust tending to withdraw the plunger from the solenoid toward its position shown in Figs. 2 and 4. When electrically energized, the strength of pull of the solenoid upon the plunger overcomes the expansive tension in spring 49 and draws magnet plunger 44 inward thus shifting its carried cam plate 43 to the position 43b shown by broken lines in Fig. 4.

In the cooperative action of cam plate 43 and tongue 37 it will be understood that the cam plate moves in a straight path of travel while the tongue must move in an arcuate path. In the normal relationship of this tongue and cam plate shown in full lines in Fig. 4, the tongue 37 occupies a notch 51 forming a branch of the main aperture 52 in the cam plate. Starting with the relationship of parts shown in full lines in Fig. 4, it will be seen that the fulcrum bracket 23 is locked against movement because tongue 37 is lodged in notch 51 until the cam plate 43 has completed a preliminary movement toward the left. Until this has occurred no movement of tongue 37 (in a direction toward the plunger 44 as required by the tongue's arcuate path of travel) can take place. Nevertheless the lodging of tongue 37 within notch 51 in no way restrains cam plate 43 from moving toward the left when the solenoid 45 is electrically energized. The beginning of the cam plate movement toward the left will shift the cam plate aperture 52 and its branch notch 51 into the broken line position 43a indicated in Fig. 4. At this point tongue 37 has become freed from notch 51 so that continued movement of cam plate 43 toward the left results in the right edge 53 of aperture 52 picking up and impelling tongue 37 to the position of parts 43b shown in Fig. 4.

In the reverse movement of the cam plate from left to right in Fig. 4, the first portion of the corresponding travel of aperture 52 constitutes lost motion relative to tongue 37, but thereafter the left edge 54 of aperture 52 picks up and impels tongue 37 ahead of it toward the right, this

tongue gradually swinging counterclockwise in Fig. 4 to its broken line position 43a in the latter figure wherein the edge of tongue 37 is nearly disposed to be received again into the notch 52 which again will then cause the tongue to become locked against movement other than by subsequent actuation through plunger 34, as represented by full lines in Fig. 4.

In the position of fulcrum bracket 23 shown in Fig. 3 and by broken lines in Fig. 1, the pivot pin 24 is swung to a position best shown in Fig. 3 which is nearly at the side edge of the platform deck 20 of the car so that the right end of the turn-tilt table 22, which in Figs. 1, 2 and 4 rests upon and is prevented from tilting downward by the platform deck 20, now overhangs and is free from restraint by the platform edge when in its broken line position in Figs. 1 and 3 so that it may tilt downward to its full line position shown in Fig. 3. In the absence of a load thereon, table 22 will not tilt downward away from its horizontal position because the load delivering end of the table contains a large aperture 56 which so much reduces the weight of this end of the table that the other end 57 at the opposite side of pivot pin 24 is the heavier. This preponderance of weight of the table end 57 is normally supported by the platform deck 20 causing the table to maintain its broken line position in Fig. 3. But if a heavy enough load 59 is carried by the table 22 in such manner that the center of gravity of the load falls on the load delivering side of pivot 26, a turning moment may thereby be set up causing the table to tilt clockwise into its full line position in Fig. 3 because the preponderance of weight is then on the load delivering end of the table. An inclined chute is thus provided by the tilted table off from which the load may slide or roll.

In Figs. 2 and 3 the indicated load object may consist of a toy wheeled vehicle 59 having two rear wheels, as 60, and two front wheels, as 61. The rear wheels in the usual manner of a toy vehicle are connected by an axle 62 which may be lodged loosely and removably within the detent notches 31 of the fulcrum bracket 23. This so positions the toy load vehicle on the turn-tilt table 22 that the center of gravity of the latter falls on the load delivering end of the table which contains aperture 56 so that this end of the table plus its load becomes heavier than the opposite end 57 of the table plus the latter's share of the load, if any, with respect to the fulcrum pivot 24. Hence, the described dispositioning of the weight of the load vehicle can cause the table 22 to tilt from its broken line position in Fig. 3 to its full line position in Fig. 3 by gravity effect alone, whereupon the vehicle axle 62 is swung upward out of and free from the detent notches 31 enabling the vehicle to roll down and off from the table. To provide guide rails to direct the load vehicle lengthwise of the table 22, the latter is provided with up-turned edge flanges 63 and with similarly up-turned inner flanges 64 which receive the fulcrum pivot pin 24 and provide a smooth bearing thrust against the sides of fulcrum bracket 23.

A conductive circuit by which solenoid 45 is furnished with electric current for pulling plunger 44 toward the left in Fig. 4 includes the grounding of one end of the solenoid winding to the metallic car platform at 66 by means of the lead 67, while the other end of the same solenoid winding terminates in a lead 68 which is soldered or conductively secured otherwise to a metallic

conductive anchorage or support element 69 on each side of the car. Element 69 comprises an electrically conductive angle bracket of bent sheet metal fixed by a rivet 70 to the stiff side plate 71 made of insulative material. One end of a fine close-wound coil 72 of preferably round springy electrical conductive wire fits tightly over the laterally extending finger 73 or reduced branch of each support element 69 which may be rectangular in cross-section and is securely held thereby thus forming a very flexible "cat's whisker" the outer free end of which constitutes a current collector shoe capable of riding yieldingly and lightly into engagement with the top edge of an electrically conductive feeder or fourth rail 75. The convexly curved wire loop surface of the outside of coil 72 is thus disposed to contact with and wipe along current feeder 75. Other characteristics of coil 72 are that its loops of conductive wire lie in a helical path having an axis disposed crosswise this feeder. Normally coil 72 forms a straight resiliently flexible elongated hollow cylinder capable of temporarily springing into a bowed shape without causing the close-wound loops of the coil to separate sufficiently to admit the current feeder 75 therebetween. The latter comprises an angle strip spanning and held fixedly on the top of the ends of two or more of the track sleepers 13 by screws 76 and together with screws 76 is insulated therefrom by separators 77.

A desirable arrangement of circuit connections and control instrumentalities for operating this improved toy is shown in Fig. 7 wherein 80 represents a variable transformer capable of stepping down a home current supply line of 110 volts to a toy output range of, say 7½ to 15 volts. In the transformer here indicated a potential of 15 volts may be constantly delivered across binding posts 83 and 82 while the potential across binding posts 81 and 82 can be modulated between 7½ volts and 15 volts by turning the voltage regulating knob 84. A line 85 connects binding post 81 with the "third" rail 14 of the track from which driving power is derived by the electric locomotive of the toy train. A line 86 connects binding post 83 with the "fourth" rail 75, and this line is interruptable by a manually operable switch 87. A line 88 connects binding post 82 with either or both of the traction rails 11 or 12.

In operation a train containing the unloading car 10 may run over the tracks of any desired toy railway lay-out at speeds determined by the voltage regulating knob 84 of the transformer 80 which will vary the potential between transformer terminals 81—82 and thereby between rails 12 and 14 without of necessity changing the potential of 15 volts always available to rails 14 and 75 from transformer terminals 83—82 through the manual switch 87. The car 10, whose chassis including platform 19 carries the vehicle 59 positioned thereon as in Figs. 1 and 2, may be unloaded by the action indicated in Figs. 1 and 3 when its current pick-up shoe, or "cat's whisker" 72, is in contact with fourth rail 75 if switch 87 then be closed. This will establish a 15 volt circuit, traceable from 83 through 86, 87, 80, 72, 68, the car carried solenoid 27 or 45, 67 and then the car platform, truck and wheels to traction rail 12 and thence back to the transformer terminal 82 through the lead 88. Upon thus being electrically energized, solenoid 45 draws into itself the magnetic plunger 44 which by movement toward the left in Fig. 4 causes the cam plate 43 to swing the fulcrum bracket 23 and with it the

turn-tilt table 22 a quarter turn from positions shown in Figs. 1 and 2 to positions shown in Fig. 3 and in broken lines in Fig. 1. Thereupon the weight of the toy load vehicle 59 becomes offset with respect to the edge of the car and tilts table 22 from its broken line position to its full line position in Fig. 3, whereupon the load vehicle rolls down and off from the turn-tilt table at the side of the track. Upon being relieved of the weight of the load vehicle, the heavier end 57 of the turn-tilt table restores the latter to its broken line position in Fig. 5 whereupon if solenoid 45 is deenergized, spring 49 acts through cam plate 43 to swing the table 22 back into longitudinal alignment with the platform of the railway car as shown in Figs. 1 and 2, ready to receive, transport and later discharge another toy load when placed thereon.

As a current pick-up shoe such as 72 is provided at both sides of the car, the fourth rail 75 may be placed on either side of the track. This and many other modifications are possible and will be suggested by the teachings of this disclosure, it being understood that load objects other than a wheeled vehicle and whether capable or incapable of rolling may be discharged from a turn-tilt table by such means as are herein provided so long as their weight can be swung about to a position sufficiently overhanging the edge of the car with respect to the fulcrum pivot 24. Where this is not the case, means for forcibly causing the turn-tilt table to assume its inclined position may be provided if desired.

The following claims are directed to and are intended to cover all substitutes and equivalents of the parts which are herein shown merely to illustrate the principles of the invention.

I claim:

1. Current collecting equipment for wheeled toys, including the combination with a track and a wheeled toy adapted to travel therealong, of an electrically conductive current feeder stationed beside and elongated in the direction of said track, a support element carried by said toy, and a flexible spring coil comprised of loops of resilient helically wound conductive wire, said coil having one of its ends anchored to said support element and having a freely flexible portion of its length projecting from said support element in such position that the convexly curved wire loop surface of the outside of said coil wipes yieldingly against said current feeder as the toy travels along said track.
2. Current collecting equipment for wheeled toys, including the combination defined in claim 1, in which the said loops of said conductive wire lie in a helical path having an axis disposed crosswise the said current feeder.
3. Current collecting equipment for wheeled toys, including the combination defined in claim 1, in which the said conductive wire is helically close wound in a manner to form a normally straight resiliently flexible elongated cylindrical coil.
4. Current collecting equipment for wheeled toys, including the combination defined in claim 1, in which the said conductive wire is resilient and forms a hollow elongated straight cylindrical coil extending crosswise past and engaging broadside with the said current feeder and is helically close-wound to enable said coil temporarily to spring into a bowed shape without causing the close-wound loops of said coil to separate sufficiently to admit said current feeder therebetween.

5. Current collecting equipment for wheeled toys, including the combination defined in claim 1, in which the said wire is round in cross section and defines a hollow cylindrical anchored end of the said coil, together with a conductive anchorage carried by said support element in insulated relation to the said toy, said anchorage including a projection of rectangular cross section occupying and supporting said hollow end of the coil.

6. Current collecting equipment for wheeled toys, including the combination defined in claim 1, in which the said anchored end of the said coil is hollow, together with an electrically insulative plate fixed on the said toy, an electrically conductive bracket of sheet metal having one portion secured to said plate and having another portion reduced in cross section and projecting to occupy and fit said hollow end of the coil in a manner to support the latter in a position projecting laterally away from said insulative plate.

7. Current collecting equipment for wheeled toys, including the combination defined in claim 1, in which the said anchored end of the said coil is hollow, together with an electrically insulative plate fixed on the said toy, an electrically conductive angle bracket having one branch secured to said plate and having another branch of reduced cross section projecting from said plate in a direction perpendicular thereto occupying and fitting said hollow end of the coil in a manner to support the latter.

8. Current collecting equipment for wheeled toys including the combination defined in claim 1, in which the said support element comprises an electrically conductive plate having a body portion of relatively large area secured on the car in insulated relation thereto and having a branch portion of reduced cross section projecting laterally away from said car occupying and supporting the said anchored end of the said coil.

RICHARD G. SMITH.
